UNITED STATES PATENT OFFICE.

ISIDORE MARKS, OF DORCHESTER, MASSACHUSETTS, ASSIGNOR TO KEYSTONE MFG. CO., OF BOSTON, MASSACHUSETTS, A CORPORATION OF MASSACHUSETTS.

PUMPING-ENGINE TRUCK.

Application filed May 8, 1926. Serial No. 107,625.

The present invention relates to four-wheeled trucks, and is particularly applicable to four-wheeled trucks the parts of which are in miniature and constructed and combined as a toy that is a substantial copy of standard construction.

The principal object of the invention is to provide a novel apparatus for compressing air and piping the compressed air to a receptacle for use, such, for instance, as discharging a liquid in a continuous stream and as an auxiliary object to design such apparatus so that it may be readily applied to toys that closely resemble a standard four-wheeled truck without making it grossly apparent that the truck is a toy because of some prominent feature that is foreign to standard construction. Accordingly, a feature of the invention comprises a toy four-wheeled truck construction having means for holding compressed air for use, an air-pump for supplying the holder with compressed air mounted beneath a hood simulating, in location and construction, a standard motor hood, and a hand-crank, for operating the air-pump, that depends from the front of the frame where the engine starting crank is located on power driven trucks. Other objects of the invention are to provide a novel toy pumping engine apparatus simulating a standard fire fighting truck for utilizing the air in the holder for discharging a liquid in a continuous stream, and to provide a simple but reliable mechanism for raising and lowering a tower for the liquid discharge hose of the toy pumping engine apparatus.

To the accomplishment of these objects, and such others as may hereinafter appear, the various features of the present invention relate to certain devices, combinations and arrangements of parts fully set forth herein-after, the advantages of which will be readily understood by those skilled in the art.

The various features of the present invention will be best understood from an inspection of the accompanying drawings illustrating the preferred form of the invention as applied to a toy, in which:

Figure 1 is a view, in perspective, showing a standard motor pumping engine truck in miniature and the connections from the imitation starting crank for placing the liquid in the supply tank under pressure;

Fig. 2 is a detail, in perspective, showing

the hood tipped back to expose the air pump 55 located beneath the hood; and

Fig. 3 is a detail, in perspective, showing the mechanism for raising and lowering the water tower for the liquid discharge hose.

The toy pumping engine truck illustrated in the drawings comprises a standard four-wheeled motor truck in miniature provided with a frame 4, a hood 5, an open cab 6, a radiator 7, a body 8, and a hand starting crank 9. All these parts simulate closely the design of a pumping engine truck mounted on a commercial Packard chassis.

Mounted on the truck between the body 8 and cab 6 is a holder for compressed air herein shown as a combined water and pressure tank 10 having a filling plug 11 through which the tank may be partially filled with water. Suitably connected to the bottom of the tank 10 is a flexible hose 12 provided with a cock 13 and terminating in a discharge nozzle 14.

In order that the tank 10 may be supplied with air under pressure to forcibly expel the water from the tank through the hose 12 and out of the discharge nozzle 14 in a continuous stream when the cock 13 is opened, an air-pump 16 is provided conveniently hidden and supported on the frame 4 beneath the hood 5. To this end the frame 4 carries a bridge 15 upon which an air-pump 16 of the reciprocating piston type is mounted. The piston of the pump is reciprocated by a piston rod 17 which is pivotally connected to a pin 18 eccentrically mounted upon a disk 19. The disk 19 is secured to the rear end of a shaft 20 journaled at its rear end in a cross girder 21 below the bridge 15. The forward end of the shaft 20 is journaled at 22 in the forward end of the frame 4. The hand-starting crank 9 is mounted on the end of the shaft 20 where it projects through the frame 4. By rotating the crank 9 the shaft 20 may be revolved to operate the air-pump 16 through the connections described. The air injected by the air-pump 16 is conducted through a flexible hose 23 to the space above the water level in the tank 10 and is there compressed.

In order to make the air-pump 16 easily accessible, the hood 5 carrying the radiator 7 and the bell 24 is provided with a pair of up-standing ears 25 which are pivoted on similar ears 26 carried by the dash-board 27 of

the cab 6. With this construction the hood 5 may be tipped from the position of Fig. 1 to that of Fig. 2 to expose the air-pump (see Fig. 2).

5 If the toy is to simulate a chemical pumping engine, as those skilled in the art will recognize is within the scope of the invention, the hose 12 will be unsupported throughout its length so that it may be coiled 10 within the body 8 when not in use. When it is desired that the toy simulate a pumping engine of the water-tower type the hose 12 is carried on or within a tower 28 supported at its base on a stand 30 carried by 15 the frame at the rear of the body 8. The tower 28 and stand 30 are pivotally connected by a transverse pin 29.

In order to provide mechanism for raising and lowering the tower 28 on its pivot 20 it carries a bracket 31 to which the eye end of an eye screw 32 is pivoted. The other end of the screw 32 threads through a nut 33 which rotates on the flat surface of a transverse yoke 34 secured at its ends to the 25 opposite sides of the body 8 and having an opening to loosely receive the screw 32. The nut 33 is in the form of a circular flanged plate the upper peripheral edge of which is toothed to convert it into a worm- 30 wheel for engagement by a worm 35 carried by a shaft 36 rotatably mounted in ears 37 on the stand 30. The shaft 36 is provided with an outboard hand-wheel 38 having a 35 crank pin 39 laterally projecting therefrom. Rotation of the hand-wheel 38 revolves the worm 35 and the worm-wheel or nut 33 thus causing the screw 32 to travel vertically and to either raise or lower the tower 28 as the 40 hand-wheel 38 is turned one way or the other.

In using the toy, as a pumping engine, the 45 cock 13 is first closed and it is seen that the tank 10 is partially filled with water. The hand-crank 9 is then actuated to drive the air-pump 16 in order to compress the air in the space within the tank 10 above the water level. When sufficient pressure has been 50 built up in the tank 10 the cock 13 may be opened whereupon the pressure will cause a continuous stream of water to be discharged through the nozzle 14.

It will be clear to those skilled in the art and with the general object of the present 55 invention in view, that the compressed air in the holder may be utilized other than to dis-

charge liquid and that changes may be made in the details of structure, the described and illustrated embodiment being intended as an exploitation of its underlying essentials the features thereof are definitely stated in their 60 true scope in the claims herewith.

What is claimed as new, is:—

1. In a toy pumping engine four-wheeled truck, a frame, a hood mounted on the front end of the frame, an air pump on the frame within the hood, a combined water and pressure tank mounted on the frame at the rear of the hood, a cab between the hood and tank, a hose for delivering water from the tank and having a discharge nozzle, a hose 65 extending from the pump to the tank, a tower for the water hose pivotally mounted at the rear end of the frame, manually operable means cooperating with the tower for raising and lowering the same, a pump operating crank of the motor starting type located at the front of the frame, and means connecting the crank with the pump, 70 all of the aforesaid parts being in miniature and constructed and combined as a toy. 75

2. In a toy pumping engine four-wheeled truck, a frame, a hood mounted on the front end of the frame, an air pump on the frame within the hood, a combined water and pressure tank mounted on the frame at the rear of the hood, a hose for delivering water from the tank and having a discharge nozzle provided with a valve, a hose extending 80 from the pump to the tank, a pump operating crank of the motor starting type located at the front of the frame, and means actuated by the crank for operating the pump to generate pressure in the tank for forcing water from the tank through the hose to the nozzle, all of the aforesaid parts being in 85 miniature and constructed and combined as a toy. 90

3. In a four-wheeled truck, the parts of which are in miniature and constructed and combined as a toy, a frame, a receptacle 100 supported thereby for receiving air under pressure, a hood simulating a motor hood supported from the frame intermediate the front wheels, an air-pump supported on the frame beneath the hood, a hose extending 105 from the pump to the receptacle, a pump operating crank of the motor-starting type located at the front of the hood, and means connecting the crank with the pump.
